(No Model.)

J. J. JOHNSTON.

METHOD OF MAKING SHOVEL BLANKS.

No. 405,416.

Patented June 18, 1889.

UNITED STATES PATENT OFFICE.

JAMES J. JOHNSTON, OF COLUMBIANA, OHIO, ASSIGNOR TO HENRY M. MYERS, OF BEAVER FALLS, PENNSYLVANIA.

METHOD OF MAKING SHOVEL-BLANKS.

SPECIFICATION forming part of Letters Patent No. 405,416, dated June 18, 1889.

Application filed April 4, 1889. Serial No. 305,920. (No model.)

To all whom it may concern:

Be it known that I, JAMES J. JOHNSTON, a citizen of the United States, residing at Columbiana, in the county of Columbiana and State 5 of Ohio, have invented certain new and useful Improvements in Methods of Manufacturing Shovel-Blanks; and I do hereby declare the following to be a full, clear, and exact description of the invention, such as will enable others skilled in the art to which it appertains to make and use the same.

My invention relates to the art of making shovels, and has for its object the production of a double shovel-blank provided with single or double handle-straps.

The invention will be hereinafter described, and particularly pointed out in the claims.

In the accompanying drawings, which form part of this specification, Figure 1 represents 20 a plan view of a bar for making blanks; Fig. 2, a perspective view of a blank severed from the bar; Fig. 3, a similar view of a blank with the projections split for forming double handle-straps at each end of the double blank; Fig. 4, a plan view of a double shovel-blank rolled or plated out; Fig. 5, a similar view of 25 one half of the double blank after having been severed from the other half, and Fig. 6 a plan view of the blank shown in Fig. 5 after 30 having been pointed.

Reference being had to the drawings and the letters thereon, A indicates the bar for making double shovel-blanks, and is claimed in my application filed herewith, Serial No. 35 305,919. The bar is severed into sections on the lines a, and blanks B formed therefrom, each blank having a projection C on each edge thereof and directly opposite each other, and the body of the blank being of a length from 40 end to end about equal to the width of a finished shovel.

When it is desired to make double shovel-blanks with single handle-straps at each end, the blank B is rolled in the direction of the 45 projections C C without splitting the projections; but when it is desired to make double shovel-blanks with double handle-straps the

projections C C are split vertically, as shown in Fig. 3. Then each part b will form a handle-strap when rolled out. The projection is split 50 by a machine suitable for the purpose, and a little cinder thrown between the parts b when they are closed upon each other and the blank rolled as in the first instance. The blank B, after having been subjected to breaking-down 55 and reducing rolls, presents the appearance of a double shovel-blank D in Fig. 4. The double blank is then severed transversely in its longitudinal center, as at c, and a single blank E, Fig. 5, produced. The blank E is 60 then subjected to a pair of pointing-rolls and drawn out into the form of the blank F, (shown in Fig. 6,) after which it is sheared, stamped, and finished in the usual manner.

Having thus fully described my invention, 65 what I claim is—

1. The method of manufacturing double shovel-blanks to the shearing-point, which consists in producing a bar with projections on its edges opposite each other, severing the 70 bar between the projections into sections of a length about equal to the width of a shovel-blade, reducing the sections by rolling them into double shovel-blanks, then severing the double blanks transversely, and finally pointing each single blank separately, substantially as described.

2. The method of manufacturing double shovel-blanks, which consists in severing sections from a bar having projections on its 80 edges opposite each other, splitting the projections, reducing the sections by rolling them in the direction of the projections and forming double shovel-blanks, then severing the double blanks transversely, and finally 85 pointing each blank separately, substantially as described.

In testimony whereof I affix my signature in presence of two witnesses.

JAMES J. JOHNSTON.

Witnesses:

S. A. TERRY,
D. C. REINOHL.
